(57) **CLAIM**

The ornamental design for a reusable container half, as shown and described.

DESCRIPTION

FIG. 1 is a perspective view of a reusable container half showing our new design;

FIG. 2 is a right side view thereof;

FIG. 3 is a top plan view thereof;

FIG. 4 is front elevation view thereof;

FIG. 5 is a bottom plan view thereof; and,

FIG. 6 is a rear elevation view thereof.

The left side view is the same as the right side view. The broken lines in the drawings are for illustrative purposes only and form no part of the claimed design.
